UNITED STATES PATENT OFFICE.

VILAS L. SNYDER, OF DOUGLAS, OKLAHOMA.

AIR-PUMP.

1,326,427.

Specification of Letters Patent. Patented Dec. 30, 1919.

Application filed September 4, 1918. Serial No. 252,614.

To all whom it may concern:

Be it known that I, VILAS L. SNYDER, a citizen of the United States, and a resident of Douglas, in the county of Garfield 5 and State of Oklahoma, have invented certain new and useful Improvements in Air-Pumps, of which the following is a specification.

My invention is an improvement in air 10 pumps, and has for its object to provide means for use in connection with double cylinder air pumps for converting them into pumps of the single cylinder type.

In the drawings:

15 Figure 1 is a vertical section of a double cylinder pump converted into a single cylinder;

Fig. 2 is a sectional detail of the lower end of the pump;

20 Fig. 3 is a partial front view at the upper end of the pump.

The double cylinder pumps consist of a base 1 of suitable size, which has internally threaded nipples 2 and 3, the nipple 2 being 25 of larger diameter than the nipple 3. A barrel 4 has threaded engagement with the nipple 2 and a barrel of smaller diameter has engagement with the nipple 3, the said barrel not being shown in the present instance.

30 The plunger 5, which is of usual construction, is connected to a plunger rod 6 having a handle 7 detachably connected therewith. In the double pump this handle is connected 35 with both plungers, namely, the plunger 5 and the plunger in the small cylinder (not shown) so that the single handle simultaneously operates the two plungers.

When the small cylinder or the packings 40 thereof becomes worn the pump must be discarded. In the present invention, however, means is provided for converting the double pump into a single pump, by removing the small barrel or cylinder and making the 45 hose connection 8 at the nipple 3. With this object in view I provide a union or coupling 9 which has an annular rib 10 inter-

mediate its ends, and both the rib and the body of the union are threaded.

Thus three connections are provided in 50 connection with the union, permitting it to be connected to nipples of the same size but with different threading, and with nipples of different sizes. The hose 8 is connected with the union 9. The top cap of 55 the double pump is also removed, and is replaced by the cap 11 shown in Figs. 1 and 3. This cap is held in place by a split collar 12 which is clamped on the barrel by means of a screw bolt and nut 13, the 60 bolt passing through radial lugs on the split collar.

The collar has upstanding lugs 14, which have openings for receiving pins 15 on the collar 11. With the attachment consisting 65 of the union 9 and the cap 11 any double cylinder pump may be quickly transformed into a simple single cylinder pump. The handle 7, it will be noticed, has two openings 16 for connection with the plunger rods 70 of the double pump. In order to make the handle fit, a single hole 17 is bored for the plunger rod 6, the said opening 17 being between the openings 16. No special tools are required for converting the double pump 75 into the single pump, and no particular skill.

It will be noticed that the union is internally threaded at both ends so that either end can be used for engagement by the 80 hose.

I claim:

In an attachment of the character specified, a split collar having means for clamping it on the barrel of a pump, a cap having 85 an opening for the plunger rod adapted to fit over the end of the cylinder, the collar having upstanding perforated lugs and the cap having pins for engagement by the lugs to hold the cap in place.

VILAS L. SNYDER.
